UNITED STATES PATENT OFFICE.

HELEN A. KEAN AND WELCOME ARNOLD, OF HARTFORD, CONNECTICUT.

CONVERTIBLE BED.

1,259,022.

Specification of Letters Patent. Patented Mar. 12, 1918.

Application filed July 6, 1915. Serial No. 38,367.

To all whom it may concern:

Be it known that we, HELEN A. KEAN and WELCOME ARNOLD, citizens of the United States, residing at Hartford, in the county 5 of Hartford and State of Connecticut, have invented new and useful Improvements in Convertible Beds, of which the following is a specification.

The present invention relates to improvements in furniture, and particularly to bedsteads.

In carrying out our invention it is our purpose to construct a bedstead in such a manner that the same may be easily and 15 quickly converted from a double bedstead to a single bedstead, from a single bedstead to a crib, and to also provide the device with a removable element which may rest upon the corner posts to arrange the device as a 20 table. We also propose to construct a bedstead of telescopic sections and to provide the same with means for limiting the sliding of the sections, as well as to so connect the sections to permit of the disassembly 25 of the parts so that the structure may be knocked down to provide a comparatively small package which can readily be positioned in a trunk or in a similar device for transportation.

30 It is a still further object of our invention to produce a convertible bedstead made up of a plurality of tubular or pipe members and which shall embody the desirable features of simplicity in construction, cheapness to manufacture, durability and strength.

It is a still further object of our invention to provide our convertible bedstead with a spring and mattress, both of which being so constructed and arranged as to permit the 40 folding of the same, so that the said elements may be readily arranged to fit the bedstead when the same is arranged in any of its various positions.

Other objects and advantages will appear 45 as the nature of the invention is more fully understood, reference being had to the accompanying drawings in which there is illustrated a simple and satisfactory reduction of the improvement to practice.

50 In the said drawings:

Figure 1 is a perspective view of a bedstead constructed in accordance with our invention,

55 Fig. 2 is a similar view illustrating the same in the form of a single bedstead,

Fig. 3 is a similar view showing the bed-

stead converted into a crib, the telescopic upper section of the head piece being lowered,

Fig. 4 is a detail side elevation showing 60 the arrangement of a board upon the upper ends of the corner posts to convert the crib into a table, the said table being shown in section,

Fig. 5 is a plan view of the springs, 65

Fig. 6 is a similar view of the mattress, and

Fig. 7 is a detail vertical longitudinal sectional view illustrating the manner in which the tubular sections are connected and the 70 means for limiting the movement of the sliding sections, and

Fig. 8 is a view of the spring clip.

As illustrated in the drawings our improved bedstead is preferably constructed 75 of a number of jointed as well as of a number of telescopic pipe sections, we having found, from experience, that such arrangement embodies the desired strength and durability as well as rendering the construction 80 comparatively cheap to manufacture. Of course, however, our improvement may be formed from other elements than tubes, that is, the non-slidable parts may be solid should we find it desirable to so manufacture the device.

In the drawings, the numeral 1 designates the foot portion of our improved bedstead, 2 the head portion, 3 one of the side members or rails, and 4 the opposite side member 90 or rail.

Both the head and foot include the usual corner posts 5—5, each of the said posts comprising a lower tubular section 6 which rests upon suitable rollers 7 connected thereto. The lower sections have their upper ends threaded to receive the vertical tubular portion 8 of a casting 9. The casting 9 includes a longitudinal tubular section 10 having interior threads which receive the 100 threaded ends of the pipe sections comprising the sides 3 and 4. The castings 9 are also provided with spaced inwardly extending tubular portions 11 and 12, the member 11 being arranged at a right angle to the vertical member 8 of the casting and, of course, at a right angle to the posts 5, while the member 11 is disposed a suitable distance from the said member 12. The members 12 are provided with interior threads to receive exterior threads provided upon the tubular members forming the end rails 13

of the bedstead. Threadedly connected with the members 8 of the castings 9 are vertically extending tubular members 14, providing the extensions of the corner posts, 5 and connected to the members 14, at the foot 1 of the bedstead, are T couplings 15, the outer ends of the vertical portions of the said couplings being provided with suitable cap pieces 16, and the angular members of 10 the T connect the corner posts with the upper tubular members 17 of the foot 1.

Similar T's 18 are arranged upon the pipe or tube extensions 19 connected with the members 8 of the castings 9 at the head of 15 the device, the said members 18 connecting the central transverse tubular sections 20 to the posts of the head.

Projecting vertically through the T's 18 and arranged for slidable movement in the 20 lower sections of the corner posts of the head, previously described, are tubular members 21 and one or both of the T's 18 are provided with a set screw 22 which contacts with the said members 21 to sustain the 25 same in proper adjusted position upon the corner posts of the head of the bedstead. Connected with the upper ends of the tubular members 21 are T's 23, the same being provided with caps 24, and affording a connection for the upper transverse bar 25 of the head. The member 25 is, of course, constructed of tubes and is threadedly secured to the T 23.

Arranged upon the central connecting 35 member 20 of the head 2 is a swinging catch 26, the same adapted to be moved to have its lipped end 27 swung over the upper member 25 of the head when the said upper portion is telescoped within the lower portion 40 of the head as illustrated in Fig. 3 of the drawings.

To provide a firm support for the bedstead, we have found it desirable to arrange centrally upon the side rails 3 and 4 suitable coupling members 28 to which are connected downwardly extending tubular members 29 which provide legs, and these legs have connected thereto suitable rollers 30.

Also to add to the strength of the structure, 50 transverse tubular members 31, 32-32 are connected to the central coupling 28 and to the portions 11 of the respective castings 9 of the corner posts. The members, 31, 32-32 are provided with removable downwardly extending tubular sections 34, 35-35 providing legs for the said transverse connecting members and these legs have arranged thereon suitable rollers 36.

All of the transverse connecting members 60 including the end rails and the sections connecting the head and foot members of the bedstead comprise each two pipe sections, one of a less cross sectional diameter than the other and each slidable or telescopic with 65 the larger section to which it is co-extensive,

and in the showing of the drawings the reduced tubular and telescopic sections are provided upon the side 4 of the bedstead, and thus it will be noted that when a pressure is applied upon the said side 4, and the 70 side 3 held against movement, the said side 4 may be moved toward the side 3, and so convert the double bed illustrated in Fig. 1 to the single bedstead illustrated in Fig.

2. Likewise the members comprising the 75 side rails 3 and 4 each comprise a reduced section or a section which is of a less cross sectional diameter than the second section of the sides, so that the reduced section may be slid or telescoped in the larger sections

80 when the device is to be converted from a single bed (Fig. 2) to a crib, as shown in Fig. 3. The larger pipe sections of the side rails are, in the showing of the drawings, arranged upon the castings 9 connected with the corner posts of the foot of the bed, but, of course, the same may be supported by the castings connected with the head of the bed if desired.

In Fig. 7 we have illustrated a detail sectional view showing the manner in which the pipe sections are removably connected with the couplings and also the manner in which the slidable or telescopic sections are prevented from being entirely withdrawn 90 from the larger sections with which they are co-extensive. It will be noted, by reference to the said Fig. 7 that the telescopic tubular members of the lesser cross sectional diameter have their ends formed with 95 flanges 38 and that the T couplings are provided with longitudinal bores of two diameters, providing a shoulder 39 between the said bores which affords a stop for the slid- 100 able section when contacted by the annular flange 38 thereof. It will be further noted, by reference to the said Fig. 7 that the stop or shoulder 39 is arranged near the end of the coupling to which is connected the larger pipe section, so that the smaller and slid- 105 able pipe section is afforded an ample bearing even when the same is drawn or pulled out- 110 ward to the limit of its sliding movement, so that no weakening of the structure is permitted by such an arrangement.

Should it be found that, from want of space or other conditions or circumstances, the room or place in which the bedstead is arranged will not permit of the arrangement of a table therein in addition to the 115 bedstead, or when it is found desirable to dispense with the employment of an ordinary table, we provide a flat member 40 which preferably has its underface arranged with a substantially rectangular flange 41, the diameter of the said flange being approximately equal to the distance in both width and length between the caps 16 and 24 of the corner posts, so that the said caps will snugly contact with the said flange 120 125 130

when our bedstead is converted into a crib, and thus the device is easily and quickly converted into a crib. Of course, in lieu of the continuous flange 41 we may connect a 5 number of boards by suitable cleats and provide longitudinally extending members similar to the longitudinal members of the flange 41, and by arranging a cloth over this structure a simple, cheap and desirable table 10 is provided.

It is, of course, necessary that we provide the bedstead with a spring and with a mattress, as it would be expensive and not at 15 all desirable that a separate spring and mattress be employed when our device is set up as a double bed, a single bed and as a crib. Therefore, as illustrated in Figs. 5 and 6 we provide a spring 42 and a mattress 43 each of which is foldable upon itself and 20 readily applicable upon our bedstead in any of its positions or arrangements.

The springs 42 comprise four distinct sections indicated by the numerals 44, 45, 25 46 and 47 respectively. Each of the sections 44, 45 is substantially square and each of the sections 46, 47, substantially oblong. The sections are of an equal width, the sections 44 and 45 being centrally connected through the medium of bands or rings 48, 30 while the sections 46 and 47 are connected respectively with the sections 44 and 45 by similar rings or bands 49. When the spring is in its flat position as illustrated in Fig. 5, the same is of a size to be arranged upon 35 the double bedstead shown in Fig. 1, and to sustain the same in proper position we employ split resilient sleeves 50 which are passed through certain of the mesh of the springs and spread over transverse connecting members (which are in the nature of slats), indicated by the numerals 32. When 40 the springs are to be employed upon a single bed, the sections 44 and 46 are folded over the sections 45 and 47, the hinged members or bands 48 retaining the sections in 45 proper position or alinement, and again the clips 50 are employed, the same passing through the double mesh of the spring and again engaging the end connecting members 50 50. When the spring is employed upon a crib (Fig. 3) the sections 44 and 45 are first swung upon their hinges 49 over the sections 46 and 47. The sections 44 and 46 are then swung over the sections 45 and 47 55 when the spring is reduced in size sufficient to be arranged upon the crib, and again the spring clips 50 are employed for retaining the springs upon the crib.

The mattress 43 also includes four distinct sections 51, 52, 53 and 54, the sections 51 and 52 being substantially square agreeing in size with the sections 44 and 45 of the spring 42, while the sections 53 and 54

are substantially rectangular corresponding in size to the sections 46 and 47 of the 65 spring. The sections 53 and 54 are entirely separated from each other, but the sections are connected with the sections 51 and 52 by a suitable tape or by the covering upon one of the faces of the mattress, and the section 51 is likewise connected with the section 52. Thus it will be noted the sections may be folded upon themselves in a manner similar to that in which the spring is folded, so that the mattress in its spread 75 position will be arranged upon the spring of a double bed, when folded centrally and longitudinally may be arranged upon the spring in the single bed, and when folded both longitudinally and transversely, the 80 same may be readily positioned upon the spring for the crib.

From the above description, taken in connection with the accompanying drawings, the simplicity of the device, as well as the 85 advantages thereof will, it is thought, be perfectly apparent to those skilled in the art to which such invention appertains without further detailed description.

Having thus described the invention, what 90 we claim is:

An extension bed comprising telescopic side and end members and transverse telescopic members connected with the side members and disposed between the end members, 95 and substantially T shaped couplers for all of the members, leg members connected with the couplers of the side and with the couplers of the intermediate members, all of said members, including the couplers being 100 made up of pipe members, the coupler members between the telescopic sides and the telescopic intermediate members having each a longitudinal bore of two diameters, the larger bore being of a less length than 105 the smaller bore and the said larger bore receiving the smaller pipe sections, and the larger bores receiving the larger pipe sections, the smaller pipe sections having their ends received in the larger pipe sections 110 formed with annular heads which engage with the inner surface of the said larger pipe sections and which are designed to contact with the shoulder between the larger and smaller bores of the couplers to limit the 115 outward movement of the smaller pipe sections with respect to the larger pipe sections.

In testimony whereof we affix our signatures in presence of two witnesses.

HELEN A. KEAN.
WELCOME ARNOLD.
